BICYCLE HANDLEBAR

Ruben L. Pawsat, Maysville, Ky., assignor to Wald Manufacturing Company, Inc., Maysville, Ky., a corporation of Kentucky

Filed Nov. 7, 1967, Ser. No. 9,317

Term of patent 14 years

(Cl. D90—11)

FIG. 1 is a front perspective view of a bicycle handlebar embodying my new design.

FIG. 2 is a perspective view of the left side of FIG. 1.

FIG. 3 is a top plan view.

FIG. 4 is a front elevational view.

FIG. 5 is a rear elevational view.

I claim:

The ornamental design for a bicycle handlebar, as shown.
